(57) **CLAIM**

The ornamental design for a multi-cartridge system, as shown and described.

DESCRIPTION

FIG. 1 is a front perspective view of a multi-cartridge system of the present design;

FIG. 2 is a bottom perspective view of the embodiment of FIG. 1;

FIG. 3 is a front view of the embodiment of FIG. 1;

FIG. 4 is a back view of the embodiment of FIG. 1;

FIG. 5 is a right view of the embodiment of FIG. 1;

FIG. 6 is a left view of the embodiment of FIG. 1;

FIG. 7 is a top view of the embodiment of FIG. 1; and,

FIG. 8 is a bottom view of the embodiment of FIG. 1.

The broken lines in the drawings illustrate the portions of the design that form no part of the claim.
